UNITED STATES PATENT OFFICE.

CHARLES FLEISCHER, OF BROOKLYN, NEW YORK.

AMUSEMENT DEVICE.

Application filed February 19, 1925. Serial No. 10,394.

To all whom it may concern:

Be it known that I, CHARLES FLEISCHER, a citizen of the United States, and a resident of the city of New York, borough of Brooklyn, in the county of Kings and State of New York, have invented a new and Improved Amusement Device, of which the following is a full, clear, and exact description.

10 This invention relates to amusement devices, an object of the invention being to provide an amusement device which will test the skill of the operator in manipulating the coin.

15 A further object is to provide a device of this character which if successfully operated will return the coin to the operator, but if unsuccessfully operated it will drop into a cash compartment, but will indicate by the 20 travel or movement it takes some answer to a question or other data in the nature of fortune telling.

A further object is to provide an apparatus of this character which can be manufactured and sold at a reasonably low price and which will most efficiently perform the functions for which it is intended.

With these and other objects in view, the 25 invention consists in certain novel features of construction and combinations and arrangements of parts which will be more fully hereinafter described and pointed out in the claims.

Figure 1 is a view in front elevation illustrating my amusement device;

30 Figure 2 is a view in rear elevation of the metal plate which constitutes my device per se removed from the cabinet with which it is designed to be connected, as shown in Figure 1;

Figure 3 is a view in vertical section on an enlarged scale on the line 3—3 of Figure 1;

35 Figures 4, 5, 6, 7 and 8 are enlarged fragmentary views in section on the lines 4—4, 5—5, 6—6, 7—7 and 8—8, respectively, of Figure 1.

1 represents a cabinet having a removable plate or plates 2, the latter preferably provided with dowels 3 at its upper end projecting into recesses 4 in the top 5 of cabinet 1 and having a lock 6 at its lower end to engage a suitable member 7 on the bottom 8 of the cabinet to secure the plate or front 2 against fraudulent removal.

On the plate 2 I secure what constitutes my improved device A, and this device in the main comprises a metal plate or casting 9.

I would have it understood that I employ this term "casting" in its broadest sense to 60 include a single member which may be cast or otherwise formed and preferably of metal.

This casting 9 is secured to the plate or front 2 by hidden screws 10 and has a flange 11 throughout the greater portion of its edge 65 so that the main portion of the casting is offset or spaced from the cabinet front 2 a distance slightly greater than the thickness of the coin to be used.

This casting 9 has a transparent plate 12 70 secured therein in any approved manner so that this transparent plate 12 discloses a series of inclined platforms or chutes 13 at opposite sides of the center line of the device over which a coin such as illustrated at 14 75 may pass in its passage into the cabinet 1.

Adjacent the top of the device a longer chute or guide 15 is provided which extends to the outside of the casting 9 and terminates in a curved receptacle 16 which will receive 80 and hold a coin 14 if the operator successfully manipulates the same to the top of the device, as will more fully hereinafter appear.

A downward extension 17 is formed on 85 the casting 9 and is made with a longitudinal slot 18 through which a knob or fingerhold 19 on a bar 20 projects. This bar 20 is guided by webs 21 formed in the casting and spaced apart, and an opening 23 is formed 90 in the casting between the webs 21 to admit a coin 14 into position above the upper end of the bar 20. This upper end of the bar 20 may be somewhat enlarged and recessed, as shown at 24, so as to afford the desired 95 support for the coins.

Adjacent the several chutes or inclined webs 13 I may locate any desired captions, as indicated in Figure 1, which will indicate or express to the operator some meaning if 100 the coin moves down that chute and falls through any of a series of openings 25 in the front 2 of cabinet 1.

The operation is as follows:

A coin is inserted through the opening 23 105 and falls into position on top of the bar 20. The operator then manually moves the bar 20 in a vertical direction, endeavoring to balance the coin and hold it on the end of the bar until it reaches a point where it will 110

roll down the chute 15 and be returned to the operator. This requires considerable skill and in most cases the coin will fall off the end of the bar 20 and roll down one of the webs or chutes 13 and fall into the cabinet. The operator reads the caption adjacent the chute and receives either information or amusement from the passage of the coin as it indicates such caption.

10 It is to be understood, of course, that the bar 20 is permitted a certain amount of lateral movement which if permitted will compel the coin to fall off the end of the bar and hence it requires a certain amount of skill to 15 move the coin successfully through the device.

Various slight changes and alterations might be made in the general form of the parts described without departing from my 20 invention, and hence I do not limit myself to the precise detail set forth but consider myself at liberty to make such slight changes and alterations as fairly fall within the spirit and scope of the appended claims.

25 I claim:

1. An amusement device, comprising a casing having a plurality of lateral coin outlets, and a movable member adapted to balance a coin and move it between said series 30 of outlets to a desired station.

2. A device of the character described, comprising a casing having a transparent front, a plurality of inclined webs or chutes formed on the casing back of the transparent 35 front and spaced from each other throughout the simple line of the casing, and a member adapted to move a coin through the spaces between said webs or chutes.

3. A device of the character described, 40 comprising a casing having a transparent front, a plurality of inclined webs or chutes formed on the casing back of the transparent front and spaced from each other throughout the simple line of the casing, and a member 45 adapted to move a coin through the spaces between the said webs or chutes, one of said chutes extending to the outside of the casing for the return of the coin and the others of said chutes direct the coin into the 50 interior of the casing.

4. A device of the character described,

comprising a casing adapted to be secured to a cabinet and having its main portion offset from the cabinet a distance slightly greater than the thickness of the coin to be 55 used, a transparent portion in said casing, chutes at opposite sides of the casing and observable through the transparent portion, a downwardly projecting extension on the casing constituting a guide, and a bar movable in said guide and adapted to move a coin by engagement with the upper end of the bar thereof, and said casing having an opening therein for positioning the coin on the upper end of the bar.

5. A device of the character described, comprising a casing adapted to be secured to a cabinet and having its main portion offset from the cabinet a distance slightly greater than the thickness of the coin to be 70 used, a transparent portion in said casing, chutes at opposite sides of the casing observable through the transparent portion, a downwardly projecting extension on the 75 casing constituting a guide, a bar movable in said guide and adapted to move a coin by engagement with the upper end of the bar thereof, and said casing having an opening therein for positioning the coin on the upper end of the bar and parallel webs on the casing at opposite sides of the opening.

6. A device of the character described, comprising a casing adapted to be secured to a cabinet and having its main portion offset from the cabinet a distance slightly greater than the thickness of the coin to be 85 used, a transparent portion in said casing, chutes at opposite sides of the casing observable through the transparent portion, a downwardly projecting extension on the 90 casing constituting a guide, and a bar movable in said guide and adapted to move a coin by engagement with the upper end of the bar thereof, and said casing having an opening therein for positioning the coin on the upper end of the bar and parallel webs on the casing at opposite sides of the opening, said extension having a longitudinal slot therein and a knob or handhold on the bar projecting through the slot.

CHARLES FLEISCHER.
